FOREIGN PATENT DOCUMENTS

DE OS 1 565 638 4/1970
(Continued)*Primary Examiner* — Patricia Palasik(74) *Attorney, Agent, or Firm* — Jon L. Woodard; David S. Willoughby; MacDonald, Illig, Jones & Britton LLP(57) **CLAIM**

What is claimed is the ornamental design for a nozzle for torch, as shown and described.

DESCRIPTION

FIG. 1 is a front perspective view of the nozzle for torch of the invention;

FIG. 2 is a left side perspective view of the nozzle for torch shown in FIG. 1;

FIG. 3 is a rear perspective view of the nozzle for torch shown in FIG. 1;

FIG. 4 is a front view of the nozzle for torch shown in FIG. 1; FIG. 5 is a rear view of the nozzle for torch shown in FIG. 1; FIG. 6 is a left side view of the nozzle for torch shown in FIG. 1;

FIG. 7 is a right side view of the nozzle for torch shown in FIG. 1;

FIG. 8 is a top view of the nozzle for torch shown in FIG. 1; and,

FIG. 9 is a bottom view of the nozzle for torch shown in FIG. 1.
